FLUID OPERATED PUMP

Granville S. Knox, Los Angeles, Calif.

Application January 3, 1933, Serial No. 649,885

13 Claims. (Cl. 103—46)

This invention relates to fluid operated pumps and has particular reference to what are commonly termed "rodless pumps" for pumping deep wells, especially oil wells.

5 In my United States Patent No. 1,909,493, issued May 16, 1933, there is disclosed a fluid operated pump incorporating a basically new feature in pump design. Essentially, that pump comprises a motor and pump piston assembly and a fluid-pressure operated valve mechanism in which the movement of the piston assembly and the valve mechanism in proper, timed sequence, is insured by so proportioning the faces of the valve and piston assemblies that the ratio of the opposite areas of valve surface exposed to operating fluid and exhaust fluid respectively, is always greater than the ratio of the opposite areas of piston surface simultaneously exposed to operating fluid and exhaust fluid, respectively; this insures complete movement of the valve to a desired new position before the piston assembly begins its next stroke.

The pump constituting the present invention is a variation of that disclosed in the aforementioned prior patent. It incorporates the same basic principles of operation with the addition of refinements that make it more practicable and more efficient in operation.

An object of the present invention is to provide a fluid operated pump having the positive and reliable valve action characterizing my rodless pump as disclosed in my Patent No. 1,909,493, that displaces equal volumes of exhaust fluid and pumped fluid on both strokes.

35 Another object of the invention is to provide a pump having the positive and reliable valve action of my original pump, in which the pump is positioned below the motor to permit using a conventional gas anchor on the pump.

40 A feature of the invention is the novel means and method of connecting the lower end of the high pressure tubing extending down through the well to the pump whereby the high pressure tubing may be readily released from the pump and vented into the surrounding exhaust tubing to permit drainage of the oil from the high pressure tubing or to blow out sand from the passages immediately above the pump.

45 50 Another feature lies in the particular construction of the pump, wherein a double seal against leakage from the high pressure passages of the pump is provided.

Other features of the invention will be apparent from the following detailed description in

which reference is made to the accompanying drawings.

In the drawings:

Figure 1 is a general view showing my pump positioned in a well casing, portions of the pump being broken away to show the inner construction.

Figures 2, 3, 4, 5, 6, 7 and 8 are detailed sectional views, taken in the plane II to VIII of Figure 11 and showing consecutively lower portions of the pump.

Figure 9 is a sectional elevational view of portions of the pump, this section being taken in the plane IX—IX of Figure 12, and showing one set of passages within the pump.

Figure 10 is a sectional view of the pump taken in the plane X—X of Figure 14, and showing the course of another set of passages within the pump.

Figures 11, 12, 13, 14, 15, 16, 17 and 18 are cross sectional views of the pump taken in the plane designated with corresponding reference numerals in Figures 3, 4, 5, and 6.

Figures 19 and 20 are simplified schematic diagrams for illustrating the operation of the pump.

Theory of operation

A complete understanding of the construction and operation of my pump can best be obtained by first following through the general construction and theory of operation with reference to the diagrammatic views constituting Figures 19 and 20, respectively. These views are identical, except that Fig. 19 shows the piston assembly and valve in their lowermost positions (at the end of their down strokes) and Figure 20 shows the piston assembly and valve in their upper positions (which they assume at the end of their up strokes).

Referring now to Fig. 19, I have shown a pump cylinder 1 and a motor cylinder 2 positioned coaxially therewith and immediately thereabove. A pump piston 3 is positioned in the pump cylinder and a motor piston 4 in the motor cylinder, both rigidly mounted on a common piston rod 5 extending not only between the motor and pump pistons 4 and 3 but upwardly beyond the motor cylinder 2 for a substantial distance through a valve chamber 6 and terminating in a passage 7 communicating with the exterior of the pump. The lower end of the pump cylinder 1 is provided with an inlet valve 8 and the pump piston 3 is provided with an upwardly opening valve 9. The upper end of the pump cylinder 1 communicates through a passage 10 with the space between an

70

85

90

100

105

110

inner tube 11 and outer tube 12 extending to the surface of the well. It will be apparent that as the pump piston 3 moves downwardly the oil or fluid in the cylinder therebelow will be forced past the valve 9 in the piston into the cylinder space above the piston and due to the displacement of the piston rod 5 some of this fluid will be forced up through the passage 10 into the exhaust pipe 12. On the subsequent upward stroke the pump piston 3 will force the fluid in the cylinder thereabove through the passage 10 into the exhaust pipe 12.

By making the area of the piston rod 5 equal to half the area of the pump piston 3, the pump will displace equal volumes of fluid through passage 10 into the exhaust pipe 12 on each stroke.

To supply operating fluid to and exhaust fluid from the motor cylinder 2, passages 13 and 14 are provided extending from respective opposite ends of the motor cylinder 2 to the valve chamber 6. A pair of ports 15 and 16 respectively connect the valve chamber 6 with the exhaust passage 10 and an inlet passage 17 connects the valve chamber 6 with the pressure pipe 11 which supplies operating fluid under pressure from the surface of the earth. The operating fluid may be forced down through the tube 11 by any suitable pump.

Positioned within the valve chamber 6 is a piston valve indicated generally at 18 which surrounds the extended upper portion of the piston rod 5. Valve 18 is provided with four outwardly extending shoulders 19, 20, 21 and 22, which seal with the walls of the chamber 6. The inner wall of the valve 18 seals with the piston rod 5 except at the point between the shoulders 20 and 21.

It will be observed that the four shoulders 19, 20, 21 and 22, on valve 18, define three concentric passages or pockets 23, 24 and 25, which pockets serve when the valve is in various positions to interconnect in a desired manner the various ports leading into the valve chamber from the passages 13, 14, 15, 16 and 17. The exact manner in which the valve functions can be most easily explained by following through the operation of the device.

In the position shown in Figure 19, the valve 18 is in its lowermost position and the pocket 24 in the valve 18 connects the passage 17 carrying operating fluid under pressure to passage 14 and leading to the top of the motor cylinder 2. At the same time pocket 25 connects the passage 13 leading from the bottom of the motor cylinder to the passage 15, leading into the exhaust passage 10. High pressure fluid from tube 11 is thereafter applied to the upper side of the motor piston 4 and the latter is maintained in its lowermost position. With the valve 18 in its lowermost position, as shown, the pocket 24 also registers with a port connected with a passage 26 in the piston rod which communicates through a second port with the extreme lower end of the valve chamber 6 below the valve 18. High pressure fluid is therefore applied against the lower end of the valve 18 and moves the latter upwardly. At the same time the fluid in the upper end of the valve chamber 6 above the valve 18 is exhausted through a passage 27 in the piston rod and through pocket 25 of valve 18 and exhaust port 15 into the exhaust passage 10. The pressure of the operating fluid being substantially greater than that of the exhaust fluid, the valve 18 moves upwardly.

Upward movement of the valve first carries the

shoulder 20 past the port connected with the passage 14, thus cutting off the supply of operating fluid to the upper end of the motor cylinder 2 and then connects the port at the upper end of passage 14 through pocket 23 with the exhaust passage 16, as shown in Figure 20. At the same time, the upward movement of valve 18 brings the center pocket 24 into position to connect the port of passage 17 with the port of passage 13 thus applying high pressure fluid to the lower end of the motor cylinder 2.

The connections described are completed slightly before the valve 18 reaches the upper limit of its stroke since the ports leading into the valve chamber 6 have appreciable longitudinal dimensions. As a result, for a short interval before the valve 18 reaches the upper limit of its stroke operating fluid is applied simultaneously both to the underside of the motor piston 4 and the valve 18.

If the design of the pump were not such as to prevent it, the piston assembly might begin to move upward before the valve completed its upward movement. Such premature movement of the piston cannot take place, however, for the reason that a greater differential between the pressure of the operating fluid and exhaust fluid is required to move the piston assembly than is required to move the valve; furthermore, this pressure differential cannot increase materially above that necessary to move the valve as long as the latter is free to move.

The differential pressure between the operating and exhaust fluids required to move the valve is less than that required to move the piston assembly for the reason that the ratio of the areas of the opposite valve faces exposed to operating fluid and exhaust fluid, respectively, is greater than the ratio of opposed areas of the piston assembly exposed to operating fluid and exhaust fluid, respectively. Thus the lower and upper end faces of the valve 18 exposed to operating fluid and exhaust fluid respectively are substantially equal. On the other hand, the only area on the piston assembly exposed to operating fluid is the lower face of the piston 4, whereas both the upper faces of motor piston 4 and the upper face of pump piston 3 are exposed to the pressure of the exhaust fluid in exhaust passage 10. The lower face of the pump piston and the upper end of the piston rod 5 are exposed only to the pressure of the fluid in the well which is relatively small and may be disregarded.

As a result of the lesser pressure required to move the valve 18 than the piston assembly, the valve continues its upward movement substantially to the upper end of the valve chamber 6. When the valve can move upward no further, however, there is then no outlet for the operating fluid which is being constantly pumped down through tube 11 and passage 17 except through passage 13 to the lower face of the motor piston 4. The pressure of the operating fluid therefore immediately rises to a value sufficient to move the piston assembly and it thereafter moves the piston assembly into its uppermost position as shown in Figure 20. During this upward movement, the exhaust fluid in the motor cylinder 2 above the motor piston 4 is exhausted through passage 14 and past pocket 23 on the valve out through port 16 into the exhaust passage 10.

To prevent the valve 18 from impacting directly against the metal end wall of the valve chamber 6 on its upward movement the passage 27 in the piston rod 5 is so dimensioned that

145

150

when the piston rod is in its lowermost position, as shown in Fig. 19, the upper end of the passage 27 is slightly below the upper end of the valve chamber 6. Therefore when the valve 18 moves upwardly it seals the passage 27 slightly before the valve reaches the end of the valve chamber. This traps a small amount of exhaust fluid between the upper end of the valve and the upper end of the valve chamber which serves as a cushion to halt the valve before the latter impacts with the end of the valve chamber. However, as soon as the piston assembly begins its subsequent upward movement the passage 27 again registers with the space above the valve 18 to permit the exhaust of the fluid formerly trapped above the valve, thereby permitting the valve to move positively but slowly into its extreme uppermost position. With both the valve and piston assemblies in their extreme uppermost positions, as shown in Fig. 20, operating fluid is supplied through passage 17, the valve pocket 24, and the passage 26 of the piston rod to the upper end of the valve chamber. At the same time the lower end of the valve chamber is connected through exhaust passage 28 in the piston rod and the lower valve pocket 23 with the exhaust port 16. The valve therefore moves downward in response to the differential pressure applied to the opposite ends thereof precisely as it moved upward on the previous stroke. When the valve reaches the lower end of its stroke it again applies fluid from passage 17 through pocket 24 and passage 14 to the upper end of the motor piston 4 and simultaneously connects the passage 13 leading from the lower end of motor cylinder 2 through valve pocket 25 and exhaust port 15 to the exhaust passage 10. The piston assembly therefore moves downward into its lowermost position as shown in Fig. 19 and the cycle of operation has been completed.

During downward movement of the valve 18 the latter, of course, opens the ports necessary to supply operating fluid to the upper side of the motor piston 4 slightly before the valve reaches its lowermost position. The piston assembly, however, does not begin its downward movement until the valve has completed its downward movement for the reason that the operating fluid and exhaust fluid are applied to the substantially equally opposed end faces on the valve 18, whereas the operating fluid is applied only to the upper face of the motor piston 4 and both the lower face of piston 4 and the lower face of the pump piston 3 are exposed to the pressure of exhaust fluid. Of course during the downward movement of the pump piston 3 the upper face of the pump piston is exposed to the pressure of exhaust fluid as well as the lower face, but, as has been previously pointed out, the area of the piston rod 5 is made substantially equal to half the area of the lower face of the pump piston 3. Therefore the exhaust fluid is applied to twice the area of the lower face of pump piston 3 as on the upper face. The overall result is that on the downward stroke of the piston assembly the downward force developed by pressure of operating fluid on the upper face of the motor piston 4 is opposed by a force resulting from the application of exhaust fluid to substantially twice the area of under surface of the piston assembly (the lower face of the motor piston 4 plus half the area of the face of the pump piston 3).

It will be observed that the piston discharges equal volumes of exhaust fluid from the motor cylinder 2 on both strokes, since the areas of the

upper and lower faces of the motor piston 4 are equal. Likewise the pump discharges equal volumes of pumped fluid on both strokes because the area of the piston rod 5 is half the area of the lower face of the pump piston 3. Since the valve 18 is symmetrical in structure, the exhaust fluid discharged from the opposite ends thereof on different strokes is equal in volume.

Pumps of the general type to which this invention relates, must be sufficiently small in overall diameter to be lowered through a well casing which in many instances is only 4 or 5 inches in diameter or even smaller. The problem of design of a pump functioning as described in connection with the schematic view shown in Figures 19 and 20 is, therefore, not a simple one. It will be observed from Figures 19 and 20 that the passages 13 and 10 must extend down past the motor cylinder 2 and that the passages 17, 13, 14 and 10 all extend down past the valve chamber 6.

80

85

90

95

Construction of a practical pump

I have found it most satisfactory to form the body of the pump, which defines the pump and motor cylinders, the valve chamber and the piston rod guides in between the cylinders and the valve chamber, from short liners machined from castings and having the passages 13, 14 and 10 formed in the walls of the liners.

Thus referring to Figures 3 to 8, inclusive, I have shown a plurality of separate liners 29, 30, 31, 32, 33, 34, 35, 36, 37, 38, 39, 40, 41, 42, 43, and 44 all compressed end to end and maintained in alignment within an outer casing designated generally at 45. The outer casing 45 may itself comprise a plurality of relatively short sections screwed together. Thus, in Figures 3 to 8 the outer casing 45 has been shown as comprising an upper section 46, intermediate sections 47, 48 and 49, respectively, and a lower section 50.

115

Referring to Figure 3, the outer casing section 47 is provided with an inwardly projecting shoulder 52 bearing against the shoulder 51 on the upper liner 29 which transmits the compression exerted downwardly on the end of the series of liners to the outer casing 45. Likewise, the lowermost liner 44 (Fig. 7) is provided with outwardly projecting shoulder 53 which bears against an inwardly projecting shoulder 54 in a coupling member 55 positioned between and joining sections 49 and 50 of the outer casing 45.

The upper and lower faces of the liners 29 to 44, inclusive, are ground to fit so that little or no leakage can occur at the joinings between sections. To prevent any possible leakage to the outside of the pump, however, packing rings 56 (Figs. 3, 4 and 7), are mounted in grooves provided therefor in the liners 29, 31 and 44, and close fitting aligning rings 57 are mounted in grooves provided therefor at the junction of each pair of liners. These aligning rings 57 form a seal around the line of contact of each adjacent pair of liners to prevent leakage to the space within the outer casing 45.

To connect the outer casing 45 to the tubing 12 for supporting the latter and for exhausting fluid to the surface, the upper section 46 (Fig. 3) of the casing is threaded onto the lower end of a nipple 58, the upper end of which (Fig. 2) is joined by a threaded coupling 59 directly to the lower end of the tubing 12.

To form the necessary high-pressure fluid connection between the pressure fluid tubing 11 extending down (Fig. 2) from the surface of the earth within the exhaust fluid tube 12, the lower

150

end of tubing 11 is joined by a threaded coupling 60 to the upper end of a sleeve 61 which extends within and in telescopic engagement with a sleeve 62 which in turn is threaded at its lower end onto a nipple 63 which in turn is joined to the upper section 46 of the pump casing 45 by screw-threads 64. The lower face of sleeve 61 is tapered and ground to form a fluid-tight connection with a correspondingly tapered upper end 10 of the nipple 63. Under normal operating conditions the weight of the pressure fluid tubing 11 maintains the lower end of sleeve 61 in fluid-tight engagement with the nipple 63.

The path of operating fluid transmitted down 15 through the tubing 11 may be traced from tubing 11 down through the sleeve 61, through the nipple 63 and into the upper end of the top liner 29 from which it enters a port 65 leading through 20 passages in the liners to the valve chamber. The 25 passages from the port 65 to the valve chamber will be described at a later point.

As shown in Fig. 3, the central cavity in the upper liner 29 extends completely therethrough but is normally sealed at a point below the port 25 65 by a plug 66. The function of this plug will be described later.

It will be observed from an inspection of Figs. 3, 4 and 5 that the liner 31 is drilled to provide the guide 7 for the upper end of the piston rod designated generally at 5, that the lower face of the liner 32, which is likewise drilled to snugly receive the piston rod 5 forms the upper end of the valve chamber 6, that liners 33, 34, 35 and 36 are drilled to provide a larger central 35 cylindrical passage constituting the walls of the valve chamber 6, and that the upper face of the liner 37 constitutes the lower end wall of valve chamber 6.

Liners 37 and 38, like the liners 31 and 32, are 40 drilled to snugly receive the piston rod 5 passing therethrough and the lower end of liner 38 constitutes the upper end of the motor cylinder 2. The walls of motor cylinder 2 are formed by central apertures of suitable size in the liners 39, 45 40, 41 and 42. The upper end of liner 43 constitutes the lower end wall of the motor cylinder 2, and the central aperture in liners 43 and 44 is dimensioned to snugly fit the piston rod 5, these liners constituting the piston rod guides 50 between the lower end of the motor cylinder 2 and the upper end of the pump cylinder 1.

The wall of the pump cylinder or barrel itself is constituted by a sleeve 67 which is compressed between the lower end of liner 44 and a plug 68. The plug 68 is in turn maintained in compression against the lower end of sleeve 67 by a bushing 74 screwed into the lower end of the bottom casing section 50.

The upper end of the sleeve 67, constituting the 60 wall of the pump cylinder, is flared outwardly at its upper end, as shown in Fig. 7, to provide a free passageway for exhaust fluid and is enlarged at the lower end, as shown in Fig. 8, to provide room for a conventional inlet valve 69 comprising a ball 70, a seat 71 therefor, and a cage 72. The seat 71 is retained in position 65 against the top of the plug 68, constituting the lower end wall of the pump cylinder, by the cage 72 which is screwed onto an upwardly projecting flange 73 in the plug 68. The inlet passage 70 for fluid to be pumped is formed by a central aperture 75 in plug 68 extending down below the valve seat 71 and communicating with the exterior of the casing 45. My device is designed 75 particularly for use in oil wells and it is de-

sirable that provision be made for the separation of gas from the oil to as large an extent as possible before the oil enters the pump cylinder. For this reason I prefer to attach a conventional gas anchor to the lower end of the pump. In 80 Figure 8 I have shown this gas anchor as comprising a perforated tube 76, the upper end of which is threaded into bushing 74.

The tubing 76 extends some distance below the bushing 74 and is attached at its lower end to 85 a cap member 77 which is of slightly larger interior diameter than the external diameter of tubing 76 and extends upwardly about tubing 76. A piece of tubing 78 is threaded into the lower end of the plug 68 and extends downward 90 some distance into the tubing 76. Anchors of the type described are old and well-known in the art and their operation is well understood by those skilled in the art.

The piston assembly

The piston rod which has heretofore been referred to generally by the reference numeral 5, is preferably tubular in construction and as shown in the drawings comprises a tube 79 closed at 100 its upper end by a plug 80 threaded therein and closed by and attached to a plug 81 at its lower end which likewise is threaded into the tube 79. The lower plug 81 also constitutes a means of attaching the tube 79 to the upper end of the 105 motor piston 82. Thus the lower end of plug 81 is enlarged to form a flange 83 fitting into the hollow upper end of piston 82. A bushing 84 is screwed into the upper end of the piston 82 about the plug 81 and bears against the upper 110 face of flange 83.

The motor piston, comprising the member 82, is symmetrical in construction and it is joined at its lower end to a tube 85 in exactly the same manner as it is joined to tube 79. Tube 85 constitutes the portion of the piston rod extending between the motor piston, designated generally at 4, and the pump piston designated generally at 3. Pump piston 3 comprises a sleeve 86 (Figs. 7 and 8) which is joined by screw threads at its 120 upper end to a valve cage 87. Valve cage 87 is provided with a shoulder 88 which engages with and holds in position a valve seat 89 which operates with a valve ball 90 positioned within the valve cage 87. The valve cage 87 is provided 125 at its upper end with an inwardly projecting flange 91 which is clamped between the lower end of tube 85 and a shoulder 92 on the lower end of a plug 93 screwed into the lower end of tube 85. The valve cage 87 is of open construction to provide 130 passages, one of which is shown at 94, for the passage of fluid from the hollow piston to the space in the cylinder thereabove surrounding the tube 85.

I have shown the pump piston 3 provided with 135 a second valve positioned at its lower end, this valve comprising a seat 95, a ball 96 and a cage 97. The cage 97 is provided with an outwardly extending flange 98 on its lower end which rests against a shoulder formed by enlarging the lower end of the sleeve 86 constituting the main body of the piston 3, and both the valve seat 95 and cage 97 are held in position by a bushing 99 screwed into the lower end of the piston sleeve 86.

Referring to Figs. 4 and 5, the exhaust passages for exhausting fluid from the respective upper and lower ends of the valve chamber 6 are constituted by grooves 27 and 28 in the outer surface of the tube 79 constituting the portion of the piston rod adjacent the valve. The passage 140

26 (Fig. 19) within the piston rod for supplying high-pressure fluid to operate the valve, comprises the central passage within the tube 79, ports 100 (Fig. 4) and 101 (Fig. 5) being provided 5 at the proper longitudinal points to register with the upper end of the valve chamber 6 and the pocket 24 of the valve, respectively, when the piston rod is in uppermost position, and with the pocket 24 and the lower end of the valve chamber 10 6, respectively, when the piston rod is in its lowermost position. Since the interior of the tube 79, constituting the passage 26, is sealed at the opposite ends of the tube 79 by the plugs 80 and 81, respectively (Figs. 4 and 6), the ports 100 and 15 101 constitute the only openings leading to and from the passage 26.

The valve structure

As previously described, the valve chamber 6 is defined by the liner 32 forming its upper end wall; the liners 33, 34, 35, and 36 constituting its cylindrical side wall, and the liner 37, the upper 20 face of which constitutes its lower end wall. The valve 18 comprises a sleeve fitting snugly about the tube 79 constituting the adjacent portion of the piston rod and sealing with both the piston rod and the cylindrical walls of the valve chamber. The sleeve is provided with shoulders 22, 21, 20 and 19, respectively, which define the three 25 pockets 25, 24 and 23, previously referred to in connection with Figs. 19 and 20. Cylindrical webs 102, 103 and 104 join the respective shoulder portions 22, 21, 20 and 19 of the valve. Web portions 102 and 104 have their inner walls continuous 30 with the inner walls of the shoulder portions which they connect so that they seal with the surface of the piston rod, but the center web 103 is cut away on the inside and provided with numerous perforations to permit the free passage 35 of fluid from the valve pocket 24 into the ports 100—101 in the piston rod tubing 79. The upper web 102 is also provided with ports 105 to permit the free passage of fluid from the grooves 27 to the pocket 25 and the lower web 104 is provided with ports 106 adjacent its lower end to permit the free passage of fluid from grooves 28 to pocket 40 23.

During operation of the pump, the movement of the valve is positively controlled by the fluid pressure applied to one or the other end thereof. However, it is desirable that when the pump is not in use, as during transportation or following its construction but preliminary to its use in a well, the valve 18 should be maintained in one end position. Otherwise, the valve might be jolted into such a position that the pump would not automatically start operating. To normally retain the valve in one end position, the liner 33 (Fig. 4) is provided with four ball detents (Fig. 13) which are mounted in radial apertures extending outwardly in the liner 33 from the central passage therein defining the wall of the valve chamber and are normally urged inwardly against the valve by springs.

Thus, referring to Fig. 13, each ball 107 is positioned in a horizontal passage 108 and has mounted back of it a small spiral spring 109 which constantly urges the ball inward into engagement with the valve. Each spring 109 is retained in position by a screw plug 110 which closes the outer end of the passage 108. The upper web 102, joining the shoulders 22 and 21 of the valve 18 (Fig. 4) is provided with surface depressions 112 and 111, respectively, the depression 111 lying opposite the ball detents 107 when the valve is

in lowermost position, as shown in Fig. 4, and the depression 112 being juxtaposed to the ball detent 107 when the valve is in uppermost position.

These detents and the cooperating depressions 80 111 tend to retain the valve in its end positions but they do not offer sufficient restraining force to prevent the free movement of the valve in response to the differential fluid pressures normally acting upon the valve to move it in the desired manner.

Operation of the practical pump

Since the theoretical operation of the pump has been fully explained with reference to the schematic diagram of Figs. 19 and 20, and the structure of a practical embodiment of the pump has been fully described, and the essential elements of the practical embodiment corresponding to the elements of the schematic diagrams have been pointed out, the operation of the practical embodiment of the pump will be fully apparent when the courses of the fluid passages have been traced.

Thus, referring to Fig. 19, passage 17 conveys 100 high-pressure fluid from the pressure tubing 11 to the center pocket 24 of the valve 18. In the practical pump disclosed, the high-pressure fluid from tubing 11 flows down through the sleeve 61 through the nipple 63 into the upper end of liner 105 29 and thence, through horizontal passage 65 (referring to Fig. 12) into vertical passages 113 formed within the wall of liner 29.

Referring now to Fig. 9, the passages 113 extend down through liners 29, 30, 31, 32, 33 and 34, 110 These passages terminate at the lower end of liner 34 (since the corresponding passages are not provided in the next lower liner 35) and, (referring to Fig. 15), are connected at this point by ports 114 to the valve chamber 6. Thus the 115 passages 113, constitute the equivalent of passage 17 in Fig. 19.

Now tracing the course of the passage identified by the reference numeral 13 in Figs. 19 and 20, we have (Fig. 14) a pair of ports 115 extending 120 outwardly from the central aperture through liner 34 forming a portion of the cylindrical wall of the valve chamber 18. The outer ends of ports 115 communicate with a pair of vertical passages 125 34, 35, 36, 37, 38, 39, 40, 41 and 42 to the lower end of the motor cylinder 2 at which point passages 116 terminate and communicate with ports 117 which extend into the lower end of the motor cylinder. The passages 116 in Fig. 10 therefore 130 correspond to the passage 13 in Figs. 19 and 20. The passage in the practical pump corresponding to passage 14 (Figs. 19 and 20) extending from the valve chamber to the upper end of the motor cylinder, is constituted by passages 118 (Fig. 135 9) which are formed in the walls of liners 35, 36, 37 and 38 and communicate at their upper ends with the valve chamber 6 through ports 119 and with the upper end of the motor cylinder through ports 120 at their lower ends. The relative 140 positioning of the passages 118 and the ports 119 and 120 is shown in the cross sectional views of Figs. 16 and 17. It will be observed from these figures, and from Fig. 9, that the passages 113 and 118 are in the same vertical plane.

The passage corresponding to exhaust passage 10 in Figs. 19 and 20, is designated in Figs. 3 to 7 and Figs 12 to 18 by the reference numeral 121. It comprises two vertical passages extending through the liners 29 to 43, inclusive, and the 150

connecting inclined passage in the liner 44 immediately above the pump cylinder. Thus, as shown in Fig. 7, these passages 121 extend directly into the chamber formed within the enlarged upper end of the sleeve 67 constituting the wall of the pump cylinder. Passages 121 communicate with the lower pocket 23 of valve 18 through ports 122 (Fig. 5) and with the upper pocket 25 of valve 18 through the ports 123 (Fig. 4).

As shown in Fig. 3, the upper ends of passages 121 in liner 29 open into a chamber 124 between the nipple 63 and the coupling member 46. Chamber 124 communicates through passages 125 (Fig. 11) provided in the coupling member 46 with the space between the sleeve 62 and the outer tubing 58. A free passage from this space up through the coupling member 59 to the space between the inner tubing 11 and the outer tubing 12 is provided, as shown in Fig. 2. The exhaust fluid, of course, passes upwardly between the outer tubing 12 and the inner tubing 11 to the surface of the earth.

As was explained in connection with schematic diagrams of Figs. 19 and 20, the space 7 above the upper end of the piston rod is connected with the space outside of the pump so that free communication between the upper end of the piston rod and the well fluid in which the pump is submerged is provided. This of course is to permit free movement of the piston rod. The passages in the practical pump leading from the upper end of the piston rod guide 7 to the exterior will now be traced.

Referring to Figs. 3 and 4, it will be observed that the upper end of the piston rod guide is defined by the central passage in liner 31. The upper end of the central passage in liner 31 in turn opens into a larger central passage 126 within the liner 30. Passage 126 is in turn connected through a plurality of lateral ports 127 with a chamber 128 formed between the outer surface of the liner 30 and the inner surface of the section 47 of the outer casing. Section 47 of the outer casing is in turn provided with perforations 129 so that free communication between the chamber 126 and the exterior of the pump is provided. The perforations 127 in the liner 30 are preferably positioned out of registration with the perforations 129 in the casing section 47. This is advantageous in that it affords opportunity for sand or other foreign matter in the well oil to settle into the bottom of the chamber defined between the outer surface of the liner 30 and the inner surface of the casing section 47, thus reducing the possibility of sand or dirt being drawn into the chamber 126 and the piston rod guide 7.

60 Connection between pressure fluid supply pipe and the pump

It will be observed from the foregoing description that the main body of the pump is secured to and supported from the outer or exhaust tubing 12 so that the pump may be run into or withdrawn from a well on the tubing 12. It is desirable to have a construction permitting the running in or withdrawing of the inner or pressure tubing 11 after the pump and the exhaust fluid tubing 12 have been placed in the well. To this end, I provide a special connection between the pressure fluid tubing 11 and the pump.

As previously described, the lower end of the pressure tubing 11 (Fig. 2) is attached by coupling 75 60 to the upper end of a sleeve 61 which slides

in telescopic engagement with an outer sleeve 62 which is rigidly attached by screw threads 64 to the upper section 46 of the pump casing. The lower end of sleeve 61 is tapered inwardly and downwardly (as shown at 131) and normally seals with a downwardly and inwardly tapered seat 130 on the upper end of the tubular member 63. The weight of the tubing 11 extending to the surface of the earth suffices to make the joint between the tapered lower face on member 61 and the tapered seat 130 fluid-tight.

However, since there is nothing other than the weight of the tubing 11 to maintain the sealing connection between the lower end of sleeve 61 and the sleeve 62, the inner tubing 11, together with sleeve 61, may be withdrawn from the well and reinserted at any time without disturbing the outer tubing 12. Reinsertion of the sleeve 61 into sleeve 62 is facilitated by outwardly flaring the upper end of sleeve 62, as shown in Fig. 2, 95 the flared end being positioned within coupling member 59 so that it does not block or plug the passage outside of sleeve 62.

It is sometimes desirable to open a passage between the inner, or pressure, tubing 11 and the outer, or exhaust, tubing 12, at a point immediately above the pump, for the purpose of blowing out sand or sludge accumulated in the outer tubing 12. I therefore provided ports 140 in the outer sleeve 62, adapted to be uncovered by lifting the inner sleeve until the lower end thereof clears the ports.

To offer a restraining force tending to prevent upward movement of sleeve 61 beyond that necessary to uncover ports 140, I provide a rod 141 within sleeve 62 having prongs 142 on its upper end. Prongs 142 are provided with outwardly projecting shoulders 143, which, upon withdrawal of the inner sleeve 61, engage with an inwardly extending shoulder 144 (Fig. 3) on the lower end 115 of sleeve 61.

The lower end of rod 141 is screwed into the plug 66, previously mentioned, which seals the high pressure passage in the upper end of liner 29 from the low pressure, or well fluid passage, 120 therebelow. Plug 66 is provided with a tapered seat 145 and is normally held in lowermost position by spring members or prongs 146 extending through the restricted passage in liner 29 and provided on their lower ends with shoulders 147 125 that bear against the lower edge of the passageway.

Under normal conditions the plug 66 is held in position not only by the prongs 146, but by the weight of fluid upon the top of the plug, 130 which, at a depth of 5,000 feet amounts to approximately 2,000 lbs. per square inch of exposed area. During insertion of plug 66, the rod 141 is guided by a spider 148 secured thereto, which centers the rod 141 within the sleeve 61. 135

When it is desired to establish a connection above the pump between the inner tubing 11 and the tubing 12, the inner tubing is lifted until the shoulder 144 on the sleeve 61 engages with shoulders 143 on prongs 142, uncovering ports 140. 140 The operator can determine when the shoulders 143 have engaged the shoulder 144 by the extra resistance to upward movement.

If it is desired to withdraw the inner tubing completely, sufficient lifting force is applied to 145 overcome the force exerted downward by the fluid head on top of the plug 66 and to force the prongs 146 inwardly, thus releasing the shoulders 147 from engagement with the lower edge of the passageway in liner 29 and permitting the plug 66 150

and rod 141 to be carried up out of the well with the inner tubing 11.

The removal of plug 66 leaves an open passageway between the outer tubing 12 and the passage 126. Since passage 126 is connected through the ports 127 and 129 with the exterior of the pump casing, all fluid standing in the tubing strings 11 and 12 can drain out into the well. This avoids a "wet job" in pulling the inner tubing 11 and the outer tubing 12 and the pump.

I claim:

1. In a fluid operated pump, an exhaust conduit for discharging exhaust fluid under pressure, a source of constant flow of operating fluid, a pump cylinder and a motor cylinder, pump and motor pistons in said respective cylinders, conduits connecting said motor cylinder to said source of operating fluid and said exhaust conduit and connecting said pump cylinder to said exhaust conduit, a common piston rod to which said pistons are connected, a piston valve for controlling flow of fluid between said motor cylinder and said source and between said motor cylinder and said exhaust conduit, said valve being operable through a stroke between two end positions to admit fluid from said source to opposite ends of said motor cylinder during substantial portions of successive strokes of said valve, auxiliary valve means to alternately admit fluid from said source to opposite ends of said piston valve whereby operating fluid is supplied simultaneously to the piston of said motor and to said piston valve during at least a portion of the stroke of the latter, said valves also operating to expose the opposite surfaces of said valve and motor piston, respectively, to the pressure of said exhaust fluid, the ratio of the surfaces of said piston valve exposed to operating fluid and exhaust fluid, respectively, being substantially the same as the ratio of the surfaces of said motor piston exposed to operating fluid and exhaust fluid, respectively, and said pump being operative to deliver substantial quantities of pumped fluid into said exhaust conduit against the pressure of said exhaust fluid, on both strokes, whereby the differential pressure between said operating fluid and exhaust fluid necessary to move said pistons through a stroke is always greater than the differential pressure necessary to move said piston valve through a stroke.

2. In a fluid operated pump, an exhaust conduit for discharging exhaust fluid under pressure, a source of constant flow of operating fluid, a pump cylinder and a motor cylinder, pump and motor pistons in said respective cylinders, conduits connecting said motor cylinder to said source of operating fluid and said exhaust conduit and connecting said pump cylinder to said exhaust conduit, a common piston rod to which said pistons are connected, a piston valve for controlling flow of fluid between said motor cylinder and said source and between said motor cylinder and said exhaust conduit, said valve being operable through a stroke between two end positions to admit fluid from said source to opposite ends of said motor cylinder during substantial portions of successive strokes of said valve, auxiliary valve means to alternately admit fluid from said source to opposite ends of said piston valve whereby operating fluid is supplied simultaneously to the piston of said motor and to said piston valve during at least a portion of the stroke of the latter, said valves also operating to expose the opposite surfaces of said valve and motor piston, respectively, to the pressure of said

exhaust fluid, the ratio of the surfaces of said piston valve exposed to operating fluid and exhaust fluid, respectively, being substantially the same as the ratio of the surfaces of said motor piston exposed to operating fluid and exhaust fluid, respectively, said pump cylinder having an inlet valve in one end communicating with fluid to be pumped, an exhaust port in the other end, said pump piston having a valved opening to admit fluid from the valve end of the cylinder to the ported end, and the piston face toward the ported end of the cylinder having substantially half the area of the opposite piston face whereby said pump delivers substantially equal volumes of fluid on both strokes.

3. In a fluid operated pump, an exhaust conduit for discharging exhaust fluid under pressure, a source of constant flow of operating fluid, a pump cylinder and a motor cylinder, pump and motor pistons in said respective cylinders, conduits connecting said motor cylinder to said source of operating fluid and said exhaust conduit and connecting said pump cylinder to said exhaust conduit, a common piston rod to which said pistons are connected, a piston valve for controlling flow of fluid between said motor cylinder and said source and between said motor cylinder and said exhaust conduit, said valve being operable through a stroke between two end positions to admit fluid from said source to opposite ends of said motor cylinder during substantial portions of successive strokes of said valve, auxiliary valve means to alternately admit fluid from said source to opposite ends of said piston valve whereby operating fluid is supplied simultaneously to the piston of said motor and to said piston valve during at least a portion of the stroke of the latter, said valves also operating to expose the opposite surfaces of said valve and motor piston, respectively, to the pressure of said exhaust fluid, the ratio of the surfaces of said piston valve exposed to operating fluid and exhaust fluid, respectively, being substantially the same as the ratio of the surfaces of said motor piston exposed to operating fluid and exhaust fluid, respectively, said pump cylinder having an inlet valve in one end communicating with fluid to be pumped, an exhaust port in the other end, said pump piston having a valved opening to admit fluid from the valve end of the cylinder to the ported end, and said pump piston having a piston rod of substantially half the cross sectional area of the piston face, said piston rod extending through the ported end of said cylinder, whereby said pump delivers substantially equal volumes of fluid on both strokes, the outer end of said piston rod being exposed to pressure of said fluid to be pumped.

4. In a fluid operated pump, a vertical pump cylinder having a valved inlet port at its lower end and an exhaust port at its upper end, an exhaust passage normally filled with exhaust fluid under pressure communicating with said exhaust port, a pump piston in said cylinder, a piston rod of substantial cross sectional area relative to the area of said piston extending upwardly from said piston through the end of and above said pump cylinder, a motor cylinder positioned above said pump cylinder and in alignment therewith, a motor piston in said motor cylinder and attached to said piston rod, said piston rod extending through the end walls of said motor cylinder both above and below, a valve chamber above said motor cylinder, and a piston valve concentrically positioned about the upper end of said piston rod within said valve chamber, auxiliary valve means

- including as an element thereof the upwardly extended portion of the piston rod within the valve chamber for selectively supplying operating fluid under pressure to opposite ends of said piston valve, and means including said piston valve for successively connecting opposite ends of said motor cylinder to a source of operating fluid under pressure and to said exhaust passage respectively. 5. In a fluid operated pump of the type described, adapted to be submerged in fluid to be pumped, a tubular shell having a pump cylinder therewithin at the bottom, a valved piston in the cylinder, an inlet valve in the bottom of the cylinder, a discharge port in the upper end of the cylinder, a piston rod extending upwardly from the piston through the upper end wall of the cylinder and terminating within said tubular shell, said piston rod having substantially half the cross sectional area of said piston whereby the pump 10 delivers substantially equal volumes of fluid in to said exhaust port on both strokes, means comprising a motor and a valve therefor positioned above said pump cylinder for reciprocating said piston rod, said rod extending completely through the motor and valve and having its upper end exposed to the pressure of the fluid in which the pump is submerged. 6. In a fluid operated pump of the type described, adapted to be submerged in fluid to be pumped, a tubular shell having a pump cylinder therewithin at the bottom, a valved piston in the cylinder, an inlet valve in the bottom of the cylinder, a discharge port in the upper end of the cylinder, a piston rod extending upwardly from the piston through the upper end wall of the cylinder and terminating within said tubular shell, said piston rod having substantially half the cross sectional area of said piston whereby the pump 15 delivers substantially equal volumes of fluid into said exhaust port on both strokes, means comprising a motor and a valve therefor positioned above said pump cylinder for reciprocating said piston rod, said rod extending completely through and beyond the motor and valve, a piston rod 20 guide above said motor and valve and sealing with the portion of said piston rod extending therethrough, an inner wall within said shell defining an enlarged central chamber above said guide and communicating therewith, said wall also defining, together with the tubular shell of the pump, an annular chamber surrounding said central chamber, and said inner wall and shell having holes extending therethrough for permitting fluid flow from the exterior of the pump to and from 25 said central chamber through said annular chamber as the piston rod reciprocates, thereby exposing the upper end of said rod to the pressure of fluid in which the pump is submerged, said annular chamber serving as a trap for solid matter in said fluid. 7. In a high pressure pump comprising an elongated member having therein elongated passages for containing fluid at high pressures, the structure comprising an outer tubular shell, a plurality of liners of smaller external diameter than the internal diameter of said shell compressed end to end within said shell, said liners having longitudinal interconnecting passages therethrough defining the high pressure fluid 30 passages of said pump and having their juxtaposed surfaces ground to seal with each other about said passages, and a tightly fitting ring surrounding the ends of adjoining liners to provide an auxiliary seal between said liners, and to align said liners, 75 the outside diameter of said ring being less than the inside diameter of said shell. 8. In a fluid operated pump of the type described, comprising a tubular shell containing a pumping mechanism supplied with high pressure operating fluid through small central tubing extending to the surface and delivering exhaust fluid and pumped fluid to the surface through larger outer tubing surrounding said central tubing, means for rigidly attaching said shell to said outer tubing, a coupling in said outer tubing positioned above said shell and defining a chamber between the juxtaposed ends of the outer tubing which it connects of larger diameter than the inner diameter of said outer tubing, a female sleeve rigidly attached to and extending upwardly from said shell within said outer tubing, having a smooth cylindrical inner surface constituting a portion of a high pressure passage for delivering operating fluid to the mechanism within said shell, the upper end of said female sleeve being flared outwardly and terminating within said chamber, and a male sleeve adapted to be rigidly attached to the lower end of said central tubing and having a smooth exterior cylindrical surface for telescoping within and sealing with said female sleeve, whereby the fluid connection between said central tubing and the high pressure passage of said pump may be made or broken by merely lowering said central tubing from the surface, the outside diameter of the flared end of said female sleeve being greater than the inside diameter of said outer tubing but less than the diameter of said chamber defined by said coupling. 9. In a fluid operated pump of the type described, comprising a tubular shell containing a pumping mechanism supplied with high pressure operating fluid through small central tubing extending to the surface and delivering exhaust fluid and pumped fluid to the surface through larger outer tubing surrounding said central tubing, means for rigidly attaching said shell to said outer tubing, a female sleeve rigidly attached to and extending upwardly from said shell within said outer tubing and having a smooth cylindrical inner surface constituting a portion of a high pressure passage for delivering operating fluid to the mechanism within said shell, and a male sleeve adapted to be rigidly attached to the lower end of said central tubing and having a smooth exterior cylindrical surface for telescoping within and sealing with said female sleeve, whereby the fluid connection between said central tubing and the high pressure passage of said pump may be made or broken by merely lowering or raising said central tubing from the surface, said female sleeve being perforated at a level intermediate its upper and lower ends whereby communication may be established through said perforation between said central tubing and the outer tubing by raising said sleeve to uncover said perforation without completely withdrawing the male sleeve from the female sleeve. 10. In a fluid operated pump of the type described, comprising a tubular shell containing a pumping mechanism supplied with high pressure operating fluid through small central tubing extending to the surface and delivering exhaust fluid and pumped fluid to the surface through larger outer tubing surrounding said central tubing, means for rigidly attaching said shell to said outer tubing, a female sleeve rigidly attached to and extending upwardly from said shell within said outer tubing and having a smooth cylindrical inner surface constituting a portion of a high 80 85 90 95 100 105 110 115 120 125 130 135 140 145 150

- pressure passage for delivering operating fluid to the mechanism within said shell, and a male sleeve adapted to be rigidly attached to the lower end of said central tubing and having a smooth 5 exterior cylindrical surface for telescoping within and sealing with said female sleeve, whereby the fluid connection between said central tubing and the high pressure passage of said pump may be made or broken by merely lowering or raising said 10 central tubing from the surface, said female sleeve being perforated at a level intermediate its upper and lower ends, means for resisting upward movement of the lower end of said male sleeve beyond a level between said perforation and the upper end 15 of said female sleeve, comprising an inwardly projecting shoulder on the lower end of said male sleeve, and a rod positioned within said male sleeve and having outwardly projecting shoulders on its upper end for engaging with said inwardly 20 projecting shoulders on the lower end of said male sleeve upon predetermined upward movement of the latter, and means for releasably anchoring the lower end of said rod to the body of the pump. 25
11. In a fluid operated pump of the type described, comprising a tubular shell containing a pumping mechanism supplied with high pressure operating fluid through small central tubing extending to the surface and delivering exhaust fluid and pumped fluid to the surface through 30 larger outer tubing surrounding said central tubing, means for rigidly attaching said shell to said outer tubing, a female sleeve rigidly attached to and extending upwardly from said shell within said outer tubing and having a smooth cylindrical 35 inner surface constituting a portion of a high pressure passage for delivering operating fluid to the mechanism within said shell, and a male sleeve adapted to be rigidly attached to the lower end of said central tubing and having a smooth 40 exterior cylindrical surface for telescoping within and sealing with said female sleeve, whereby the fluid connection between said central tubing and the high pressure passage of said pump may be made or broken by merely lowering or raising 45 said central tubing from the surface, said female sleeve being perforated at a level intermediate its upper and lower ends, means for resisting upward movement of the lower end of said male sleeve beyond a level between said perforation 50 and the upper end of said female sleeve, comprising an inwardly projecting shoulder on the lower end of said male sleeve, and a rod positioned within said male sleeve and having outwardly 55 projecting shoulders on its upper end for engaging with said inwardly projecting shoulders on the lower end of said male sleeve upon predetermined upward movement of the latter, means defining a low pressure passage in said pump body below said high pressure passage and communicating with the exterior of said pump shell; means defining a central, vertical, restricted passage connecting said low and high pressure passages and having a tapered seat at its upper end, a tapered plug on the lower end of said rod for sealing said restricted opening when said rod is in lowermost position, the lower end of said plug comprising means extensible through said restricted passage and resiliently engaging the lower end of said restricted passage to resist upward movement of said plug and rod but releasable upon application of a predetermined lifting force to said rod through said central tubing. 60
12. In a fluid operated pump of the type described, comprising a tubular shell containing a pumping mechanism supplied with high pressure operating fluid through small central tubing extending to the surface and delivering exhaust fluid and pumped fluid to the surface through larger outer tubing surrounding said central tubing, means for rigidly attaching said shell to said outer tubing, a female sleeve rigidly attached to and extending upwardly from said shell within said outer tubing and having a smooth cylindrical inner surface constituting a portion of a high pressure passage for delivering operating fluid to the mechanism within said shell, and a male sleeve adapted to be rigidly attached to the lower end of said central tubing and having a smooth exterior cylindrical surface for telescoping within and sealing with said female sleeve, whereby the fluid connection between said central tubing and the high pressure passage of said pump may be made or broken by merely lowering or raising said central tubing from the surface, said female sleeve being perforated at a level intermediate its upper and lower ends, and means for resisting upward movement of the lower end of said male sleeve beyond a level between said perforation and the upper end of said female sleeve, comprising an inwardly projecting shoulder on the lower end of said male sleeve, and a rod positioned within said male sleeve and having outwardly projecting shoulders on its upper end for engaging with 145
13. In a fluid operated pump of the type described, comprising a tubular shell containing a pumping mechanism supplied with high pressure operating fluid through small central tubing extending to the surface and delivering exhaust fluid and pumped fluid to the surface through larger outer tubing surrounding said central tubing, means for rigidly attaching said shell to said outer tubing, a female sleeve rigidly attached to and extending upwardly from said shell within said outer tubing and having a smooth cylindrical inner surface constituting a portion of a high pressure passage for delivering operating fluid to the mechanism within said shell, and a male sleeve adapted to be rigidly attached to the lower end of said central tubing and having a smooth exterior cylindrical surface for telescoping within and sealing with said female sleeve, whereby the fluid connection between said central tubing and the high pressure passage of said pump may be made or broken by merely lowering or raising said central tubing from the surface, said female sleeve being perforated at a level intermediate its upper and lower ends, and means for resisting upward movement of the lower end of said male sleeve beyond a level between said perforation and the upper end of said female sleeve, comprising an inwardly projecting shoulder on the lower end of said male sleeve, and a rod positioned within said male sleeve and having outwardly projecting shoulders on its upper end for engaging with 150

said inwardly projecting shoulders on the lower end of said male sleeve upon predetermined upward movement of the latter, means defining a low pressure passage in said pump body below 5 said high pressure passage and communicating with the exterior of said pump shell, means defining a central, vertical, restricted passage connecting said low and high pressure passages and having a tapered seat at its upper end, a tapered

plug on the lower end of said rod for sealing said restricted passage when said rod is in lowermost position, and stop means on said rod engaging with said male sleeve when the latter is in lowermost position for maintaining the rod 80 in lowermost position, said stop means comprising a plurality of radiating arms for centering said rod within said female sleeve.
